UNITED STATES PATENT OFFICE.

DICK B. WILLIAMS, OF CHICAGO, ILLINOIS, ASSIGNOR TO W. OGDEN COLEMAN, OF CHICAGO, ILLINOIS.

LOW-FUEL ALARM.

Application filed March 21, 1924. Serial No. 700,939.

This invention relates to low fuel alarms or signals having special utility in automobile fuel supply systems to warn the driver of the necessity of replenishing his fuel supply.

To that end the invention contemplates, a simple, practical, and reliable device which may be readily applied to automobile fuel supply systems of the vacuum type wherein the fuel is elevated from a tank at the rear of the automobile, intermittently in increments by the vacuum produced in the intake manifold of the engine. In that connection the invention contemplates a construction which may be readily and quickly applied to fuel systems already installed without the necessity of involving expensive or complicated alterations.

A further object of the invention is to provide a device which operates directly in conjunction with the vacuum created in the usual vacuum tank of a standard type of vacuum fuel supply system.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawings, in which:—

Figure 1 is a diagrammatic view illustrating the application of the invention.

Figure 2 is a vertical sectional view illustrating the novel circuit closer device.

Figure 3 is an enlarged detail sectional view of the main fuel supply tank showing the low fuel level indicating means.

Figure 4 is a detail sectional view taken on the line 4—4 of Figure 3.

Figure 5 is a diagrammatic view of a modification.

Similar reference characters designate corresponding parts throughout the several figures of the drawings.

As previously indicated the present invention is primarily designed to be employed in connection with a standard type of vacuum fuel supply system which includes a main tank T located usually at the rear of the automobile, and a combined vacuum pump and auxiliary tank A which is

connected with the main tank T by a feed line B. The auxiliary tank A is connected with the carburetor C by a pipe-line D and is also connected to the intake manifold M of the engine by the usual vacuum or suction tube E. At the point where the auxiliary tank is equipped with the filler plug F it is proposed to insert a novel circuit closer device whereby it will be responsive to the vacuum formed in the tank A intermittently to draw fuel from the tank T into the auxiliary tank.

The circuit closer device 1 preferably operates in conjunction with a lamp 2 or equivalent signal which is a part of an electrical circuit 3 that includes the storage battery 4 or other source of electric energy. The lamp 2, or its equivalent, may be located in any convenient position within the view or range of the driver and is intended to be intermittently operated under normal conditions by the vacuum which exists at intervals in the auxiliary tank A, but when the fuel supply reaches a predetermined low level it is intended that the lamp 2 shall glow at longer intervals, and in fact, substantially continuously.

To attain that result the end of the feed pipe B which communicates with the tank T is especially equipped to properly indicate the desired low level of fuel in the tank. That is to say, the extension portion B' which is positioned within the tank T is preferably flattened out at its lower end as indicated at 5, and at a predetermined point above the lower constricted end, the body 90 of the pipe is provided with lateral openings or holes 6. Normally, the fuel in the tank will cover these holes and therefore the vacuum tank A will pull fuel through the constricted open end 5 as well as the openings 6. However, when the fuel drops to the level of the openings, the vacuum in the tank A will persist for a longer period due to the fact that the fuel will be drawn up through the bottom of the pipe 5 by the 100 rush of air through the holes 6 but in greatly reduced volume, thereby taking a much longer period to replenish the reservoir in the pump A and consequently causing the lamp 2 to be illuminated for a longer period 105 of time. It will, of course, be understood that the area of the holes 6—6 is less than the area of the restricted open end 5 of the

pipe, thereby permitting fuel to be drawn up through the feed pipe B into the tank A, but requiring a longer period for the fuel lifting operation, as previously explained.

5 Also it will be observed by reference to the drawings, particularly Fig. 3, that the size or total area of the said holes 6—6 is greater than the vent hole in the filler cap in order to provide a proper proportion between the 10 said respective openings whereby the suction actuated element of the circuit closer will properly operate; while on the other hand as already noted the size or total area of the hole 6—6 must not be too large in 15 proportion to the opening or supply source at the bottom of the feed pipe, otherwise the circuit closer would act but the gas supply would fail. Consequently, the proper relative proportion between the size of the holes 20 6 and the vent hole in the filler cap of the fuel supply or storage tank T, and the opening or hole at the bottom of the pipe B' in the said tank are important considerations in the practical carrying out of the present 25 invention. It is by reason of this feature of the invention that the same provides for giving a warning or signal for a definite and arbitrary reserve of fuel, and after giving this warning or signal the apparatus 30 continues to function in supplying fuel automatically and without change of any parts or without any manual adjustment for the predetermined arbitrary period.

The circuit closer device 1 may be of any 35 desired construction, but a practical and reliable embodiment is shown in Figure 2 of the drawings, wherein it consists of an outer casing or shell 7 and an inner vacuum-responsive plunger 8. The outer shell 7 is 40 preferably provided with a threaded nipple portion 9 for fitting into the usual filler opening of the auxiliary tank A and is also formed with a constricted bore 10 thereby providing an interior abutment wall 11 45 against which one end of the compression spring 12 may rest. This spring 12 is housed within the tubular shank portion of the piston or plunger 8 and normally maintains the same projected outwardly, the 50 outward movement of the plunger 8 being limited by a stop bracket S. It will, therefore, be understood that the spring 12 normally maintains the plunger in an outwardly advanced location whereby the head 55 13 of the plunger or piston is spaced away from the end of the outer shell 7.

A contact collar 14 is clamped to the upper edge of the shell 7 and insulated therefrom by an insulation sleeve or ring 15, 60 while the screw 16 which clamps the collar in position also serves as a binding terminal for a wire of the circuit 3 which connects the collar with the lamp. As previously explained the said circuit 3 includes the lamp 2 and the battery 4, the latter being

grounded to the frame or other part of the automobile as usual thereby rendering all of the metallic parts of the circuit closer device, except the collar 14, also a part of the ground of the circuit 3. Therefore, when 70 a vacuum is created in the tank A and exhausts the air from the chamber of the hollow piston or plunger which houses the spring 12, the head 13 of the piston will engage the contact collar 14 and temporarily 75 close the circuit to the lamp 2 thereby to provide a transient signal of a duration corresponding to the duration of the vacuum in the tank A. Under normal conditions the period of the vacuum is short, but under 80 the condition of low fuel as previously explained, the vacuum is prolonged thereby giving a prolonged and substantially continuous warning signal.

Without further description it is thought 85 that the distinguishing features of the invention will be clear so that it will be understood that modifications in the arrangement of the parts may be resorted to without departing from the invention. For instance, 90 as suggested in the diagrammatic view, Figure 5, the circuit closer device designated in its entirety by the numeral 1 instead of being fitted directly to the crown or head of the vacuum tank could with advantage be 95 mounted on and in the line of the feed or suction pipe B between the tank T and the vacuum pump or tank A. Such an arrangement of the circuit closer in the line of the 100 suction pipe between the fuel tank T and the vacuum pump or tank A will be particularly advantageous in those installations in which the vacuum pump A is provided with a strainer at the terminus of the suction pipe B connecting therewith, because with 105 the circuit closer 1 located between said strainer and the tank T the efficacy of the signal will not be impaired due to partial interruptions of the vacuum through the action of said strainer. Furthermore the modified arrangement shown in Fig. 5 may be 110 more convenient in some installations, and the functioning thereof remains the same as when fitted directly to the vacuum pump or tank.

115 Other modifications and changes in the form, proportion and minor details of construction may be resorted to without departing from the spirit of the invention or from the scope of the appended claims.

I claim:—

1. A low fuel alarm of the class described, 120 including in combination with the vacuum tank and fuel tank of a vacuum fuel supply system, a circuit closing device in communication with the vacuum tank so as to be subjected to the pressure therein, said device having a signal controlling element actuated by the suction, a signal rendered operative and inoperative by said signal controlling 125 130

element, and means for causing the signal to be noticeably prolonged when the fuel supply has fallen below the reserve.

- 5 2. A low fuel alarm of the class described, including the vacuum tank and fuel tank of a vacuum fuel supply system, a signal, and means cooperating with said system for causing the signal to be operated intermittently at short intervals during the normal 10 functioning of the vacuum system when the fuel supply is above a predetermined reserve level, and to be maintained for noticeably longer intervals when the fuel supply has fallen below said reserve level.
- 15 3. A low fuel alarm for vacuum fuel supply systems including in combination with the vacuum tank and fuel supply tank, a suction actuated circuit closing device inserted in the system in communication with 20 the vacuum tank so as to be subjected to the vacuum therein, an electric signal circuit included in said device, and means whereby the circuit closing device will be operated intermittently at short intervals during the normal 25 functioning of the system when the fuel

supply is above a predetermined reserve level, and to be maintained for noticeably longer intervals when the fuel supply has fallen below said reserve level, said means including a feed pipe extension in the fuel supply tank having supplemental openings arranged at a predetermined distance above the inlet to said pipe and of less area than the latter.

- 30 4. A low fuel alarm of the class described including the vacuum tank and fuel tank, of a vacuum fuel supply system, a circuit closer operated by suction, means whereby the circuit closer may be operated intermittently for periods of different duration, said 35 means including a feed pipe extension arranged in the fuel supply tank and having lateral openings arranged at the predetermined low fuel level, and the end of said pipe being flattened to provide an inlet or 40 relatively constricted size or of a greater area 45 than said lateral openings.

In testimony whereof I hereunto affix my signature.

DICK B. WILLIAMS.
